WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN CONTROL.

1,316,543.

Specification of Letters Patent. Patented Sept. 16, 1919.

Application filed January 15, 1915. Serial No. 2,384.

To all whom it may concern:

Be it known that I, WINTHROP K. Howe, a citizen of the United States, and a resident of the city of Rochester, in the county of Monroe and State of New York, have invented new and useful Improvements in Automatic Train Controls, of which the following is a specification.

This invention relates to the automatic control of movable vehicles, and particularly such movable vehicles as move upon railway tracks.

The primary object of this invention is such a connection and arrangement of the means located on a vehicle which contacts with devices placed along the right of way, as will enable the movement of the train to be controlled irrespective of the particular end of the car, upon which the devices are placed, is ahead during the movement of the train.

Other objects and advantages will appear as the description of the invention progresses, and the novel features of the invention will be particularly pointed out in the appended claims.

In describing the invention in detail, reference is had to the accompanying drawing, wherein has been illustrated a preferred physical embodiment of the invention by a single figure which is a schematic illustration of a railway car with applicant's invention applied thereto.

Numerals 1 designates one rail of a railway track of which 2 designates the other rail.

The wheels of the car are designated by 3, 4, 5, and 6, and the axles connecting the wheels, by 7 and 8, and the journal boxes supporting the axles, by 9 and 10. The journal boxes support side bars 11 and 12, which for simplicity are assumed to be made of suitable insulating material. These side bars at any appropriate place, as at either end thereof, support contacting shoes, as 13, 14, 15 and 16, all of which are of identical construction and comprise enlarged upper portions 13¹, 14¹, 15¹ and 16¹, which thereby form shoulders, which, by contacting with the projecting members 17, 18, 19 and 20, respectively, prevent the shoes 13, 14, 15 and 16 from being depressed too far when not in contact with a ramp, as 21. Between the members 17, 18, 19 and 20 and collars, as 13², 14², 15² and 16², are located springs 22, 23,

24 and 25, which positively move the shoes 13, 14, 15 and 16 respectively to their lower position, when they are not in contact with a ramp, as 21.

When the members 13, 14, 15 and 16 are in their lower positions, as shown, the upper enlarged ends are out of contact with the resilient members 26, 27, 28 and 29, which then contact with the members 30, 31, 32 and 33 respectively. When any one shoe is raised, however, that shoe causes a resilient member, as 26, 27, 28 or 29, located just above it, to move out of contact with the corresponding member 30, 31, 32 or 33. This upward movement of shoe 13 is caused by its contacting with a ramp, as 21.

With all of the parts in the position as shown in the drawings the relay 34 is energized by a circuit in which current flows as follows: One terminal of the battery 57, wires 36 and 37, armature 34¹, wire 38, member 32, member 28, wire 39, member 29, member 33, wire 40, member 26, member 30, wire 41, member 27, member 31, wires 42 and 43, relay 34 and wire 44 to the other terminal of the battery 57. Current flowing in the above traced path will maintain the energization of relay 34 just so long as none of the movable members 26, 27, 28 or 29 is moved from the position in contact with the members 30, 31, 32 or 33. If any one of the shoes 13, 14, 15 or 16, however, should contact with a ramp, as 21, some one of the movable members would be moved out of the position shown and the relay 34 would become deenergized, but if at the same time the ramp 21 is energized the relay 35 would become energized through a circuit as follows: One terminal of the battery 45, wire 46, switch-arm 47 in the closed position, wire 48, ramp 21, shoe 13, wires 49, 50 and 51, relay 35, wire 52, journal box 9, axle 7, wheel 4, rail 2, wire 53 to the other terminal of the battery 45. Current flowing in the above traced path would energize the relay 35 and cause its armature 35¹ to be raised, thereby closing a circuit through the relay 34, in which current flows as follows: One terminal of battery 57, wires 36 and 54, armature 35¹, wires 55 and 43, relay 34 and wire 44 to the other terminal of the battery 57. The last two above traced circuits would be formed by the contacting of any shoe, as 13, 14, 15 or 16, with an energized ramp, as 21, and would so cause an energiza-

tion of relay 34, which would then be maintained energized by the circuit hereinbefore described, which includes in series with it all of the movable members 26, 27, 28 and 29.

5 The relay 34 has another armature 34², which may be employed in any well known or appropriate manner, in any way desired, to control the movement of the train, as for instance, by acting upon a brake valve 10 magnet 56.

From the above description it will be seen that the car carrying the shoes may move upon the track with either its head end forward, or its rear end forward, and 15 will always have a shoe, as 13, 14, 15 or 16, in position to be contacted by the trackway devices as ramps located on one side only of the trackway, and that the contact of any shoe with a ramp will control the relay 34 20 exactly as would the contact of any other shoe with a ramp, or that the shoes may contact with and coöperate with a ramp placed on either side of the trackway.

Although I have particularly described 25 the construction of one physical embodiment of my invention, and explained the operation and principle thereof; nevertheless, I desire to have it understood that the form selected is merely illustrative, but does 30 not exhaust the possible physical embodiments of the idea of means underlying my invention.

What I claim as new and desire to secure by Letters Patent of the United States, is:

35 1. In a system for protecting railway traffic, means for establishing communication between a railway track and a vehicle adapted to travel thereon comprising impulse devices located at intervals along the 40 track, two coöoperating impulse devices carried by the vehicle on each side thereof, said impulse devices on the vehicle on either side thereof being located at the same distance from the corresponding end of the vehicle, 45 whereby an impulse may be transmitted to the vehicle at the same point in its travel irrespective of the direction in which it is headed.

2. In a system for protecting railway 50 traffic, means for establishing communication between a railway track and a vehicle adapted to travel thereon comprising ramps located at intervals along the track, two contact shoes carried by the vehicle on each side 55 thereof and adapted to form electrical contact with said ramps and to be mechanically moved thereby, the contact shoes on either side of the vehicle being located the same distance from the corresponding end 60 of the vehicle, traffic protecting means having a tendency to assume its active condition, a circuit for normally holding said traffic protecting means in its inactive condition controlled separately by said contact shoes, 65 and a partial circuit having multiple

branches to said shoes for conducting electrical energy from the ramps to the traffic protecting means on the vehicle.

3. In a system for protecting railway traffic, means for establishing communication 70 between a railway track and a vehicle adapted to travel thereon comprising ramps located at intervals along the track, two contact shoes carried by the vehicle on each side thereof and located the same distance 75 from the corresponding end of the vehicle, said shoes being arranged to make electrical contact with said ramps and to be moved mechanically by engagement with said ramps, a normally closed circuit controller 80 governed by each shoe and opened upon movement thereof, a normally closed circuit including in series said circuit controllers; a normally open partial circuit on the vehicle having branches in multiple 85 which terminate at said contact shoes, and traffic protecting means on the vehicle controlled jointly by said normally closed circuit and said normally opened partial circuit, said protecting means being maintained normally inactive by current in either 90 circuit and having a tendency to assume its active condition.

4. In a traffic protecting system for rail- 95 ways, in combination: a vehicle and a track therefor; ramps located at intervals along the track; a shoe carried by the vehicle on each side thereof, said shoes being arranged 100 to engage said ramps and being adapted to be displaced by such engagement; a normally closed circuit controller operated by each shoe and opened upon displacement of that shoe; a control relay on the vehicle having a pickup circuit and a normally closed stick circuit including said relay, said 105 stick circuit including said circuit controllers in series; another relay on the vehicle controlling the pickup circuit of the first relay; a normally open partial circuit including said another relay and having 110 multiple branches terminating at the respective shoes; and traffic controlled means for supplying electrical energy to said ramps for energizing said another relay.

5. In a system for protecting railway 115 traffic, the combination with a vehicle and automatic train control apparatus therefor, of means for establishing communication between the track and the vehicle comprising trackway impulse devices located at intervals along the track and adapted to co-operate with impulse devices carried by the vehicle, the vehicle carried impulse devices being located one on each side of the vehicle and substantially the same distance 120 from the corresponding end thereof, said trackway impulse devices having a tendency when coöperating with a vehicle carried impulse device to set the train control apparatus on the vehicle into operation, and 125 130

means for placing the trackway impulse devices into condition to prevent such operation of the train control apparatus.

6. In a system for protecting railway traffic, the combination with a vehicle and automatic train control apparatus therefor, of a control relay on the vehicle for governing said apparatus having a stick circuit and a pickup circuit, impulse devices located at 5 intervals along the track, impulse devices carried by the vehicle one on each side 10

thereof and each adapted to coöperate with the trackway impulse devices and cause interruption of the stick circuit, and means for placing the trackway impulse devices in condition to cause energization of the pick-up 15 circuit of the control relay.

WINTHROP K. HOWE.
